United States Patent Office.

EDWARD MARTIN, OF BURLINGTON, VERMONT.

Design No. 2,823, dated November 5, 1867.

DESIGN FOR MOULDINGS.

The Schedule referred to in these Letters Patent and making part of the same.

TO ALL WHOM IT MAY CONCERN:

Be it known that I, EDWARD MARTIN, of Burlington, in the county of Chittenden, and in the State of Vermont, have invented a certain new and useful Design for Mouldings; and do hereby declare that the following is a full, clear, and exact description thereof, reference being had to the accompanying drawings, making part of this specification.

Figure 2 represents my design, A representing a piece of frame moulding, having cut in it open scroll or figured work, either plain or carved. This scroll or open figured work may be sawed, cut, cast, or otherwise made, from wood, paper, or other material, and used with the moulding.

I may use this design either plain or gilded, or with any color or colors for the background.

What I claim, is the within-represented design to be used on mouldings for frames, as is herein set forth. In testimony that I claim the foregoing I have hereunto set my hand this 12th day of September, 1867.

EDWARD MARTIN.
